ABSTRACT OF THE DISCLOSURE

A backlog device for fireplaces having three spaced apart large diameter pipes with a pair of smaller diameter pipes relative to the interior, in order to allow the fire place to give off more heat while requiring less wood to achieve this purpose.

This invention relates to fireplace devices, and more particularly to a backlog for fireplaces.

It is therefore the main purpose of this invention to provide a backlog for fireplaces which will consist of a plurality of large diameter pipes which are welded to a pair of spaced apart small diameter pipes.

Another object of this invention is to provide a backlog for fireplaces which will have the small diameter pipes welded to the bores of the large diameter pipes eccentrically which will enable the device to lay against the back of the fireplace and will prevent the device from rolling forward when the fire goes out.

A further object of this invention is to provide a backlog for fireplaces which will be of such construction as to keep from turning over when the fireplace is full of wood, and the spacing between the pipe elements of the device is such that there will be sufficient room for a draft when the wood is placed against the backlog device.

Other objects of the present invention are to provide a backlog for fireplaces which is simple in design, inexpensive to manufacture, rugged in construction, easy to use and efficient in operation.

These and other objects will be readily apparent upon a study of the following specification together with the accompanying drawing wherein:

FIGURE 1 is a front elevational view of the present invention shown partly broken away; and

FIGURE 2 is a section taken along the lines 2—2 of FIGURE 1.

According to this invention, a backlog 10 for fireplaces is provided with a pair of large diameter or outer pipes 11 on each end of backlog 10 which are spaced apart from the center by an outer pipe 11' of similar diameter. A pair of spaced apart small diameter inner pipes 12 are secured within the ends 13 of pipes 11 and 11'. Pipes 12 are welded eccentrically to the bores 14 of pipes 11

2

and 11'. A pair of T-shaped configurated bars 15 are welded to the bottoms of the outer periphery of pipes 11 and provide support means for backlog 10 upon the and-irons, shown in phantom (FIG. 1), within the fireplace (not shown). Each of pipes 11 and 11' is provided with an elongated slot 16 in the top thereof to allow the passage of air within the backlog 10.

In use, backlog 10 may be made in various sizes for various size fireplaces. To prevent the backlog 10 from rolling forward when the fire goes out, the weight is distributed rearwardly by welding pipes 12 eccentrically within the bores 14 of pipes 11 and 11'. The eccentric construction of backlog 10 permits a better draft to the wood being burned in the fireplace and also provides a means for the fireplace to throw out more heat while using less wood than normally would be used without the use of the instant invention.

What I now claim is:

1. A backlog device for a fireplace comprising:
  - (a) at least two outer pipes of large diameter having opposed open ends,
  - (b) at least one inner pipe having an outer diameter less than the inner diameters of said outer pipes and adapted to be received substantially longitudinally within the open ends of said outer pipes, and
  - (c) means securing said inner pipe within said outer pipes so that the opposed ends of said outer pipes are spaced apart and the longitudinal axis of said inner pipe is eccentric to the longitudinal axes of said outer pipes.
2. The invention according to claim 1 in which each of said outer pipes has an air opening through the wall of the pipe.
3. The invention according to claim 1 comprising three of said outer pipes and two of said inner pipes, said outer pipes being substantially axially aligned, there being one inner pipe within and between the opposed ends of each pair of adjacent outer pipes, the eccentricity of said inner pipes being such as to create a moment about the longitudinal axes of said outer pipes in the same direction when said outer pipes are mounted in a fireplace.
4. The invention according to claim 1 further comprising bar support members fixed to the bottoms of two of said outer pipes for supporting said backlog in a fireplace so that said backlog has a front and a rear, the longitudinal axis of said inner pipe being behind the longitudinal axes of said outer pipes when said backlog is supported in said fireplace by said bar members.
